UNITED STATES PATENT OFFICE.

WILLIAM J. TETREAULT, OF MOOSUP, CONNECTICUT.

SKIRT HANGER AND STRETCHER.

942,525.

Specification of Letters Patent.

Patented Dec. 7, 1909.

Application filed June 24, 1909. Serial No. 504,170.

To all whom it may concern:

Be it known that I, WILLIAM J. TETREAULT, a citizen of the United States, residing at Moosup, in the county of Windham and 5 State of Connecticut, have invented certain new and useful Improvements in Skirt Hangers and Stretchers, of which the following is a specification, reference being had to the accompanying drawings.

10 This invention is a device for hanging and stretching ladies' skirts.

The object of the invention is to provide a simple and practical device of this character which may be readily placed within a 15 skirt to stretch the same and keep it in proper shape free from wrinkles and by means of which the skirt may be conveniently suspended in a closet or the like.

15 A further object of the invention is to provide a device of this character which may be adjusted to permit it to be used in different sized skirts.

With the above and other objects in view, the invention consists of the novel features 20 of construction and the combination and arrangement of parts hereinafter fully described and claimed, and illustrated in the accompanying drawings, in which—

Figure 1 is a side elevation showing the 25 improved skirt hanger and stretcher, the waist band clamp being shown raised and open in full lines and in closed position in dotted lines; Fig. 2 is a horizontal section through the top of the device showing the 30 waist band clamp in closed position; and Figs. 3 and 4 are sectional views taken, respectively, on the planes indicated by the 35 lines 3—3 and 4—4 in Fig. 1.

My improved skirt hanger and stretcher comprises a top piece or member 1 to which are 40 pivotally connected two side members 2, the diverging lower ends of which are connected by an extensible bottom member 3. The top member is preferably formed from a 45 channeled metal strip of U-shape in cross section, as shown in Fig. 3, and each of the side members 2, which latter are preferably longitudinally extensible, are made from flat 50 strips or sections 4, 5, the opposing ends of which overlap and are slidably engaged with each other. Said opposing ends of the two sections 4, 5 of each member 2 have secured upon them bands 6, which slidably receive the opposing section and which contain set 55 screws 7 by means of which said sections may be clamped against movement with respect

to each other in adjusted position. The upper ends of the sections 4 are pivoted at 8 in the channeled upper piece or member 1 and the lower ends of the sections 5 are similarly pivoted, as at 9, to the outer ends of two strips or sections 10, 11 which form the bottom or lower member 3. The sections 10, 11 have on their inner ends surrounding bands 12 containing set screws 13 by means of 60 which said sections may be secured in adjusted position.

14, 14 denote two springs arranged between the upper member and the two side members for actuating the latter outwardly 65 or away from each other to stretch the skirt which surrounds them and thereby hold the skirt in proper form or shape and free from creases. Each of the springs 14 is preferably formed from a piece of wire bent to 70 form a coil 15 and having its upper end secured at 16 in the channeled upper member 1 and its lower end secured at 17 to one of the sections 4, said springs being arranged 75 diagonally so as to cross each other, as 80 clearly shown in Fig. 1.

For the purpose of more effectively retaining the skirt upon the frame, a waist band engaging clamp is provided upon the 85 top piece or member 1. This clamp consists of two resilient clamping strips 18 arranged on opposite sides of the channeled member 1 and adapted to clamp the waist band against the same. Said clamp strips or springs 18 are pivoted by means of a transverse rivet 90 or similar pivot 19 to an extended end 20 of the member 1, said pivot 19 being arranged adjacent to the inner ends of the strips 18, which latter have said inner ends united by a loop 21 around the side bars of which the 95 extremities of said strips 18 are bent, as shown at 22. The free end of one of the strips 18 is similarly bent, as at 23, around a similar loop 24 which serves as a keeper and is adapted to be swung over the free 100 end 25 of the other strip 18, as shown in Fig. 2.

For the purpose of suspending the frame or form a hook 26 is provided. The stem or shank of the latter extends through a slot 105 in the upper edge of the upper member 1 and is bent around a rivet or similar fastening 27 arranged in the central portion of said member 1, as clearly shown in Figs. 1 and 2 of the drawings.

In using the invention, the skirt to be hung and stretched is placed over the frame

parts in the position shown in Fig. 1, the 35
waist band is then placed around the upper
member 1 and the clamping strips or springs
18 are swung downwardly from their full
line position to their dotted line position so
as to hold the waist band against the oppo-
site sides of the member 1, the free ends of
said strips 18 being then united by means
of the keeper loop 24. The set screws 13
10 are then loosened so that the springs 14 will
move the side members 2 outwardly to
stretch the skirt. Said set screws may be
then tightened to retain the frame in ad-
justed position. It will be seen that by
15 loosening the set screws 7 the side members
may be varied in length according to the
skirt used upon it.

Having thus described the invention what
is claimed is:

20 1. A device of the character described
comprising a channeled connecting member
having its open edge downturned, side mem-
bers pivoted in the channel of said connect-
ing member, a waist band clamp to co-act
25 with said connecting member, a suspending
means upon said connecting member, coil
springs each having one end connected to
said connecting member, and its other end
connected to one of the side members, and a
30 longitudinally extensible means connecting
the side members.

2. A device of the character described
comprising an upper connecting member,
side members pivoted to said connecting

member, means for holding said side mem-
bers in spaced relation, a waist band clamp
35 having spring members pivoted on opposite
sides of the connecting member on one end
of the same, and means for uniting the free
ends of said spring clamp members to cause
40 the latter to retain the waist band against
opposite sides of said connecting member.

3. A device of the character described
comprising an upper member, a suspending
hook thereon, side members pivoted to the
45 upper member, an extensible connecting
member between said side members, springs
for actuating said side members away from
each other, a waist band clamp consisting
50 of resilient clamping strips pivoted on oppo-
site sides of the upper member, and means
uniting the free ends of said clamping strips.

4. A device of the character described
comprising an extensible frame having an
upper member, waist band clamping means
55 consisting of resilient strips pivoted on op-
posite sides of said upper member at one
end, a loop uniting the pivoted ends of said
strips and a keeper loop carried by the free
end of one strip and adapted to receive the
60 free end of the other strip.

In testimony whereof I hereunto affix my
signature in the presence of two witnesses.

WM. J. TETREAULT.
